COMBINED LOCK AND PROTECTOR
ADAPTED FOR USE WITH PERCOLATOR
TOPSWilliam Andrew Deuring, Cleveland Heights,
Ohio

Application February 19, 1934, Serial No. 712,054

8 Claims. (Cl. 53—3)

My invention relates to tops for percolators and more particularly to a combined lock and protector adapted for use with percolator tops.

In the usual construction of percolators, the cover is provided with a glass dome or top detachably connected to the cover and held therein by means of lugs or projections which engage with the inner periphery of the opening formed in the cover. One of the objections to this arrangement is that the glass top frequently falls out of the cover when the percolator is opened for cleaning or inspection, with the result that the top is broken. It sometimes happens that the top in falling, even though it is not broken, strikes some other object such as a cup and breaks it. Another difficulty encountered in the use of conventional mountings for the tops is that the hot liquid is free to contact directly with the glass and the resultant expansion causes the top to crack.

My invention is designed to overcome the deficiencies of the prior art arrangements and consists essentially of a combined protector for the glass and locking means for holding the top securely in position in the cover. The protector portion of the device comprises an enclosed member positioned within the glass top directly over the riser tube, and constructed and arranged to prevent hot liquid from contacting with any portion of the glass. Locking means are associated with the protector by means of which it is held in the operative position and the glass top is securely locked to the percolator cover.

An object of my invention is to provide an improved lock and protector for percolator tops.

Another object of my invention is to provide a protector for percolator tops wherein liquid is prevented from contacting with the top.

Still another object of my invention is to provide a protector arrangement for percolator tops whereby forced percolation is effected, thus preventing the coffee from boiling over.

A still further object of my invention is to provide a fastening device for percolator tops by means of which a top can be easily removed and replaced.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements in their useful applications to the particular constructions, which for the purpose of explanation, have been made the subject of illustration.

In the drawing:

Figure 1 is a sectional view of a percolator top showing my improved protector and locking device mounted therein.

Fig. 2 is a plan view of the inside of the top shown in Fig. 1.

Fig. 3 is a detail view of the fastening means.

Fig. 4 is a sectional view of a percolator top showing a modified form of the invention.

Fig. 5 is a plan view of the inside of the top shown in Fig. 4.

Fig. 6 is a detail view of the locking means used with the protector showing Figure 4; and

Fig. 7 is a detail view of this locking means showing the interior surface thereof.

Referring to the drawing and more particularly to Figures 1 and 2, there is shown an upper portion of the body 1 of a percolator having a cover 2, with glass top or dome 3 mounted therein. The cover member 2 is of conventional construction, hinged to the percolator body 1 and provided with a downwardly extending flanged portion 4, defining an opening in the cover to receive the top 3. The inner periphery of the opening is recessed as at 5 to accommodate projections formed on the glass top.

The top is also of conventional type, having an upper portion 6, forming a hand grip by means of which the percolator cover may be opened or closed, a peripheral bead 7 and a skirt portion 8 having lugs or projections 9 formed thereon. In the present arrangement the top is further provided with recesses 10 at diametrically opposite points on the skirt portion, said recesses being adapted to receive fastening elements to hold the top securely to the cover, as will be explained in detail hereinafter.

The improved percolator top protector and locking device comprise a cylindrical body portion 11 having a conical shaped closed end 12. It will be noted that the apex 13, of the closed end of the protector, is expanded slightly so that it extends above the normal lateral surface of the conical portion. The purpose of this construction is to direct the flow of coffee or other liquid in the desired direction away from the deflector with minimum splashing incidental to the abrupt change in direction of flow of the liquid.

The open end of the protector is serrated, forming projections 14 which provide separate paths for the liquid as it flows away from the top of the protector and drops back into the percolator. 5 Extending outwardly from the cylindrical portion 11 are two support arms 15 formed with lock members or hooks 16 at the ends thereof. Each hook comprises a downwardly extending portion 17, a horizontal piece 18, and an upwardly inclined portion 19 terminating in a bent over end 20 adapted to seat in one of the recesses 10.

In applying my improved protector and percolator top fastening device to a cover, the glass is inserted in the opening formed in the cover, 15 with lugs 9 registering with the recesses 5 and bead 7 resting upon the flanged portion 4 of the cover. The top is thereafter turned so that the lugs 9 move out of the recesses and contact with the inner periphery of the opening to hold the 20 top in the seated position. The protector is then inserted in the top, with the closed end 13 directly over the riser tube 21, after which the ends 20 of the hook members are inserted into the recesses 10 formed in the skirt portion.

25 The glass top is thus securely locked to the cover and may be subjected to severe handling without any possibility of its becoming loose or dropping out. In this connection it will be noted that the bent over portion of the hook contacts 30 with the edge of the flanged portion 4 and that the recesses 10, which slope inwardly, together with the hook ends, provide a wedging action which serves to draw the top down tightly into the cover. Although use may be made of the 35 lugs 9 to effect a preliminary locking, it will be understood that with my improved locking arrangement that the lugs can be eliminated and the protector can be applied to a cover and securely lock the top to the same without moving 40 the lugs out of register with recesses 5.

For the purpose of preventing the deflector from 45 rocking about its points of contact with the skirt 8, the horizontal portions 18 are provided with extensions 22 whereby movement of the protector with respect to the top is prevented. It is important that the apex 13 of the protector always 50 remain directly over the riser tube for the reason that the design of the protector is such that the hot liquid or coffee first strikes the conical portion and is directed away from the top in a manner to prevent excessive agitation of the liquid.

55 Referring to Fig. 3, which is a detailed view of one of the fastening elements, it will be seen that the hook end 20 is bent over so that it will easily slide into one of the recesses 10 and at the same time contact with the flanged portion 4 thus drawing the glass down into tight engagement with the sides of the flanged portion forming 60 the opening in the cover. The hook members are arranged to give a spring action so that when the ends 20 coincide with the recesses they will slide under the flanged portion 4 and seat in said recesses.

65 Referring to Figs. 4 and 5, I have shown a modification of the arrangement disclosed in Figure 1, wherein the fastening elements are adapted to engage with lugs or projections 23 formed on the skirt portion of the glass top. In this arrangement the protector device is the same as that shown in Figure 1, however, the hook members are provided with openings 24 adapted to fit over the lugs 23 and hold the protector in the locked position on the top. It will be noted that the ends 70 25 of the fastening elements are bent outwardly

and extend over a substantial portion of the flange 4 defining the opening in the cover member.

80 Referring to Figs. 6 and 7, there is shown detailed views of the fastening means used in connection with the protector disclosed in Fig. 4 and it will be observed that above the openings 25, the ends of the hooks are pressed inwardly as at 26 so that in applying the hook to a top, the portion 26 engages with the projection and due to the configuration of this portion, movement of the hook away from the projection is prevented. It will be further noted that the curvature of the end of the hook 25 is such as to permit the flanged portion 4 to seat between the end portions and the skirt of flanged portion 4 to seat between the end portions and the skirt of the top whereby a tight engagement is effected between the parts.

85 It will now be appreciated that I have provided an improved protector device for the tops of percolators which is of general application to percolators and adapted to prevent the hot coffee or other liquid from contacting with any portion of the glass. The concave design of the protector causes the water to be forced downwardly over the coffee grounds and the resultant forced percolation destroys the air or gas bubbles in the liquid thereby preventing the coffee from boiling over.

90 100 While I have shown and described the preferred embodiment of my invention, I wish it to be understood that I do not confine myself to the precise details of construction herein set forth, by way of illustrations, as it is apparent that many changes and variations may be made therein, by those skilled in the art, without departing from 105 the spirit of the invention, or exceeding the scope of the appended claims.

95 110 What is claimed is:

1. A deflector adapted for insertion into percolator tops comprising a cylindrical body portion 115 closed at one end, arms extending outwardly from the body portion and means to attach the arms to the percolator top, the deflector being positioned with respect to the conventional riser tube, whereby the top is protected from contact with 120 liquid discharged from the tube.

125 2. A deflector adapted for insertion into percolator tops, comprising a cylindrical body portion having a conical shaped closed end, arms extending outwardly from the body portion and means to attach the arms to said percolator top, the deflector being positioned and arranged with respect to the conventional riser tube, whereby the top is protected from contact with liquid discharged from the tube.

130 135 3. A deflector adapted for insertion into percolator tops comprising a cylindrical body having a conical shaped closed end, said body being serrated at its open end, arms extending outwardly from the body portion and means to attach the arms to a percolator top, the deflector being positioned with respect to the conventional riser tube, whereby the top is protected from contact with liquid discharged from the tube.

140 145 4. A combined protector and lock for percolator tops comprising a cylindrical body portion having a conical shaped closed end adapted for insertion into a percolator top, arms extending outwardly from the body portion and means formed with the arms to attach the protector to the top and lock the top to a percolator cover, the protector being positioned with respect to the conventional riser tube, whereby liquid discharged from said tube is prevented from contacting with the percolator top.

5. In combination with a percolator having a cover and a top, including a body portion having recesses formed in the periphery thereof, means to protect the top from contact with liquid discharged from a riser tube, comprising a cylindrical member insertable in the top in spaced relation with respect to the tube, said member having a closed end, arms extending outwardly from the member, hook members formed at the end of the arms adapted for engagement with the recesses formed in the body portion of said top and means formed with said hook members to prevent the arms from tilting with respect to the top. 80
- 10 5. In combination with a percolator having a cover and a top, including a body portion having recesses formed in the periphery thereof, means to protect the top from contact with liquid discharged from a riser tube, comprising a cylindrical member insertable in the top in spaced relation with respect to the tube, said member having a closed end, arms extending outwardly from said member and means formed on said arms adapted for insertion into the recesses formed in the body portion of said top. 85
- 15 6. In combination with a percolator having a cover and a top, including a body portion having recesses formed in the periphery thereof, means to protect the top from contact with liquid discharged from a riser tube, comprising a cylindrical member insertable in the top in spaced relation with respect to the tube, said member having a conical shaped closed end and a serrated open end, arms extending outwardly from said member and means formed on said arms adapted for insertion into the recesses formed in the body portion of said top. 90
- 20 7. In combination with a percolator having a cover and a top, including a body portion having recesses formed in the periphery thereof, means to protect the top from contact with liquid discharged from a riser tube, comprising a cylindrical member insertable in the top in proximity to the riser tube, said member having a conical shaped closed end and a serrated open end, a plurality of arms extending outwardly from said member, hook members formed at the ends of the arms adapted for insertion into the recesses formed in the body portion of the percolator top and means formed with said hook members adapted to prevent tilting movement of the arms with respect to the top. 95
- 25 7. In combination with a percolator having a cover and a top, including a body portion having recesses formed in the periphery thereof, means to protect the top from contact with liquid discharged from a riser tube, comprising a cylindrical member insertable in the top in proximity to the riser tube, said member having a conical shaped closed end and a serrated open end, a plurality of arms extending outwardly from said member, hook members formed at the ends of the arms adapted for insertion into the recesses formed in the body portion of the percolator top and means formed with said hook members adapted to prevent tilting movement of the arms with respect to the top. 100
